UNITED STATES PATENT OFFICE.

JOHN WOODVILLE, OF WASHINGTON, INDIANA.

IMPROVEMENT IN RAILWAY FROGS.

Specification forming part of Letters Patent No. 140,230, dated June 24, 1873; application filed April 26, 1873.

To all whom it may concern:

Be it known that I, JOHN WOODVILLE, of Washington, in the county of Daviess and State of Indiana, have invented a new and Improved Railway Turn-out, of which the following is a specification:

My invention consists of a turn-out for mining-railways, constructed with particular reference to the cars used in mines, in which it is necessary to have the wheels revolve on the axles, on account of the short curves necessary on such roads, and which said wheels, in consequence of so working, have considerable lateral play, which necessitates different conditions in the switches, guard-rails, and frogs from those which suffice for cars in which the wheels are fixed on the axles. Such wheels, furthermore, have to be provided with much wider flanges, in consequence of the unevenness of the road-beds, which are only temporary, the tracks being moved from time to time, as in the progress of the work the faces of the veins recede from the tracks; and these wide flanges necessitate the arrangement of the rails so as to prevent the wheels running on the flanges as much as possible at the switches. The invention comprises improvements in the form or construction of points of switch-rails *h d.*

Figure 1 is a longitudinal section of the turn-out with the movable tongue, showing the supports. Fig. 2 is a plan view of the turn-out with the movable point; also the frog and the guard therefor; and Fig. 3 is a plan view of the turn-out with the stationary points only to the switch.

Similar letters of reference indicate corresponding parts.

A represents the wing-plate for the outside rail, and B the one for the inside rail, each containing a short section, C D, of the principal rail, and a guard-rail; E F; also the stationary switch-points G H. The peculiarities of these points are: The pointed end G terminates at such a point in the line of the outside rail I of the branch track that the gage is increased on the radial line *a* about one and a quarter inches; and the pointed end of H is so arranged that the gage on the radial line *b* is increased about an inch and a half, so that, notwithstanding the lateral play of wheels on the

axles—which is sometimes considerable in consequence of the wearing of the hubs and collars—they will be switched off on the curve with certainty in case the car is pulled by the team to the left, so that the front wheel at that side comes against the rail D for the distance between the point of G and rail D, being thus increased, will insure the passage of the left-hand wheel on the right of point G. But if the car is to continue on the straight track the point G, being so distant from the rail C, will insure the passage of the wheels of that side between them; and, in case the wheels of the other side should run to the right far enough to strike the end of rail J, the oblique side *d* of point H will throw them back.

This fixed-point switch I find, by practical experiment, works very satisfactorily without a movable tongue; but, in some cases, where the turn-out is not very short, so that the team will not naturally turn out enough to pull the car over into the switch, it is desirable to employ one, which, in such a case, I apply as represented in Figs. 1 and 2, making the point G a little shorter, with a concave end, and pivoting the tongue M at the concave end of it by a pin, N, extending down through the wing-plate, and having an arm, O, fixed on it, and extending outside of rail C a suitable distance, and connected, by a rod, P, to the lower end of the vertical lever Q, pivoted at R to a post or any suitable support, and having an arm, S, projecting each way, whereon to suspend a weight, V, for holding the tongue open or closed, as may be desired, the weight being put on one arm to hold it open, and the other to hold it closed.

The upper extension of the lever may be used to shift the tongue by hand, if necessary; but, as switch-tenders are not employed in mines, and the drivers are required to shift the switches, I propose to have a cord or rod, T, extending along the track each way, so that when it is desired to have the car take the course which the tongue would, under the influence of the weight, prevent it from taking, the driver can shift the tongue while riding on the car by reaching out and pulling the cord.

I propose to arrange the points above the bottom of the plate A on rests, so that it will

be, for the most part of its length, free to pass over the earth and small objects on the plate A.

W and X are guard-points, arranged in such local relation to the switch as to prevent the loose wheels of the cars from striking the rails at y, and thus guide them into the narrow spaces z.

Having thus described my invention, I claim as new and desire to secure by Letters Patent—

1. The fixed points G and H, constructed and arranged slightly inclined, or at such an

angle to the rails, that the gage of the track is increased on the radial lines a and b, as and for the purpose specified.

2. The arrangement of the tongue on rests, supporting it on the bottom of plate A, in the manner described.

JOHN WOODVILLE.
